Primary Examiner — Raphael Barkai(74) *Attorney, Agent, or Firm* — Richard T. Matthews**CLAIM**

The ornamental design for an adjustable optical assembly, as shown and described.

DESCRIPTION

FIG. 1 is a front perspective view illustrating an adjustable optical assembly, with an example of a pair of glasses connected thereto illustrated in broken lines;

FIG. 2 is a front view thereof;

FIG. 3 is a back view thereof;

FIG. 4 is a side view thereof;

FIG. 5 is an opposing side view thereof;

FIG. 6 is a top view thereof; and,

FIG. 7 is a bottom view thereof.

The broken lines shown in FIGS. 1-7 are for illustrative purposes only and form no part of the claimed design.
